DUPLICATING MECHANISM

Hubert Jagger, Chicago, and John W. Hernlund,
La Grange, Ill., assignors to Ditto Incorporated,
a corporation of West Virginia

Application March 29, 1933, Serial No. 663,416

10 Claims. (Cl. 101—133)

The invention relates to duplicating mechanism and is particularly adapted to be embodied in duplicating machines of the flat bed type.

A preferred form of the invention is embodied 5 in a hectograph machine which comprises a flat platen over which a gelatin band is disposed. A carriage slidably mounted in the machine may be reciprocated over the gelatin band to feed sheets to be duplicated to the gelatin band and to strip 10 them therefrom. The carriage is provided with platen and pressure rolls and a paper tray which guides the sheets to be duplicated between the platen and pressure rolls. The platen roll is rotatably journaled in a yoke pivoted in the carriage, a handle being provided whereby the operator 15 of the machine may oscillate the yoke to raise and lower the platen roll, the platen roll being lifted out of its functionally operative position with respect to the pressure roll and the gelatin band when a sheet to be duplicated is to be fed between the platen and pressure rolls.

Improved means is provided for alining the forward edges of the sheets to be duplicated. This means comprises an angle shaped margin 25 bar fixed to the free ends of spaced arms or levers which are pivoted in the carriage and are adapted to displace the margin bar into and out of its functionally operative position with respect to the platen roll. The means for displacing the margin bar comprises a lost motion connection 30 between the levers and the yoke which journals the platen roll. Means is provided for yieldingly holding the margin bar in its functionally operative position during the time a sheet of paper is being fed between the platen and pressure rolls and during the time the platen roll is being lowered to clamp the paper between itself and the pressure roll. This insures that the sheets to be duplicated will be alined properly with the 35 data on the gelatin band.

The carriage is provided with means actuated by the yoke for rotating the pressure roll during the downward movement of the platen roll so that the forward edge of a sheet of paper disposed 45 between the platen and pressure rolls will not be withdrawn from engagement with the margin bar.

Other objects and advantages will become apparent as the following detailed description progresses, reference being had to the accompanying drawings, wherein—

Fig. 1 is a plan elevation of a duplicating machine which embodies the invention.

Fig. 2 is an enlarged section taken on line 55 2—2 of Fig. 1.

Fig. 3 is a section taken on the same line as Fig. 2, but showing some parts of the mechanism in changed positions.

Fig. 4 is a section taken on the same line as Figs. 2 and 3, but showing some of the parts in 5 changed positions.

Fig. 5 is a section taken on line 5—5 of Fig. 2.

Fig. 6 is a section taken on line 6—6 of Fig. 5.

Fig. 7 is a fragmentary side elevation of one 10 of a pair of levers which carry a margin bar embodying the invention.

Fig. 8 is a section taken on line 8—8 of Fig. 2, and

Fig. 9 is a fragmentary perspective view of 15 the improved margin bar.

Referring now to the drawings wherein a preferred embodiment of the invention is illustrated, the reference character 10 designates generally the frame of a hectograph machine of the flat bed type. The machine comprises a platen 11 secured to the frame by the screws 12 (Figs. 1 and 2). Slidably journaled in the frame 10 and adapted to be reciprocated over the platen 11 is a carriage which is designated generally by the reference character 13. The carriage 13 comprises a frame 14 provided with a paper feeding tray or guide 15. A shaft 17 journaled in the carriage frame 14 is provided with a handle 18 whereby the operator of the machine may oscillate the shaft to raise and lower a platen roll 19, the platen roll 19 being journaled in arms or levers 20 fixed to the shaft 17. The shaft 17 and the levers 20 form a yoke. Rotatably journaled in the carriage frame 14 is a pressure roll 21 preferably formed of metal. The platen roll 19 co-operates with the pressure roll 21 to feed 30 sheets of paper to a gelatin band 23 trained over the platen 11. The platen roll 19 is preferably formed from sponge rubber and is preferably more yielding than the gelatin coating 40 of the gelatin band 23. Pivoted on one of the levers 20 by a screw 25 is a rack bar 26 having teeth engageable with a pinion 27 constrained to rotate with the pressure roll 21. (See Fig. 6.) The rack bar 26 is urged yieldingly against the 45 pinion 27 by a leaf spring 28 fixed to the carriage frame 14 by bolts 29. The free end of the leaf spring is engageable with a notch 31 formed in the rack bar 26, the construction being such that when the platen roll 19 is in its raised or functionally inoperative position as illustrated in Figs. 2 and 3, the free end of the spring 28 rests in the notch 31 and yieldingly prevents 50 displacement of the rack bar so that through the medium of the associated lever 20 and the 55

shaft 17 the handle 18 is held in the position wherein it is shown in Fig. 2. So long as the lever remains in the position wherein it is shown in Fig. 2, the platen roll 19 is retained in its functionally inoperative position. When the handle 18 is displaced angularly in a clockwise direction (Fig. 2) to lower the platen roll 18, the rack bar 26 will rotate the pressure roll 27 in a counter-clockwise direction (Fig. 6) to prevent counter-clockwise rotation of the platen roll 19, which counter-clockwise rotation of the platen roll would tend to withdraw the sheets being fed into the machine from a margin bar hereinafter described. It will be noted that when the platen roll 19 is in its lowermost position, the teeth of the rack bar 26 do not engage the pinion 27. Means is provided for locking the platen roll 19 in its lowermost position. This means comprises a latch member 35 pivoted to the carriage frame 14 by a pin 36. The latch member 35 is provided with an arm 37 engageable with a wear plate 38 on one of the levers 29. The latch member 35 is provided with another arm 39 engageable by a dog 40 fixed to a shaft 42 provided with a lever 43 (Fig. 1) whereby the shaft 42 may be displaced angularly to cause the dog 40 to disengage the latch member 35 from the wear plate 38. The latch member 35 is also provided with an extension 42a engageable by a dog 44 pivoted in the frame 10, the construction being such that when the carriage 13 is returned to its home position at the right hand end (Fig. 1) of the frame 10, the dog 44 will engage the extension 42a and disengage the latch member 35 from the wear plate 38. The latch member 35 is urged yieldingly into its locking position by a spring 46.

The mechanism described above is substantially identical with that shown and described in the co-pending application of Alfred Marchev and John W. Hernlund, Serial Number 663,404, filed March 29, 1933. The operation of the mechanism is substantially as follows: When a sheet is to be duplicated, it is placed in the paper guide or tray 15 and permitted to gravitate down between the platen roll 19 and the pressure roll 21 until it abuts against a margin bar 50, the platen roll 19 being in its uppermost position at this time (Fig. 2). The handle 18 is then displaced angularly by the operator in a clockwise direction (Fig. 2) to lower the platen roll 19 and it will be readily understood from an inspection of Fig. 3 that when the platen roll 19 engages the pressure roll 21 there is a tendency of the platen roll 19 to rotate in a counter-clockwise direction (Fig. 3) so that it will withdraw the forward edge of the paper from engagement with the margin bar. Such counter-clockwise rotation of the platen roll 19 is prevented by the rack bar 26 which rotates the pressure roll 21 in a counter-clockwise direction (Fig. 3) and thus causes it to rotate the platen roll 19 in a clockwise direction (Fig. 3). This rotation of the platen and pressure rolls holds the forward edge of the paper in engagement with the margin bar 50 and also provides sufficient paper to form the curve or bend 46 therein when the platen roll is lowered from the position wherein it is shown in Fig. 3 to the position wherein it is shown in Fig. 4. It will be readily understood, of course, that the rack bar 26 and the pinion 27 may be proportioned and designed to rotate the pressure roll through any desired angle. In the present instance, the rack bar and the pinion insure that the forward edge

of the paper will be positioned directly beneath the axis of rotation of the platen roll 19 when the platen roll is in its lowermost position (Fig. 4).

The margin bar 50 is preferably formed from sheet metal and is preferably angle shaped. At its ends, the margin bar 50 is provided with integral lugs 51 which are riveted to the free ends of arms or levers 52 pivoted at their upper ends to the carriage frame 14, pins 55 being provided for this purpose. The upper end of each lever 52 is rounded and is provided with a V-shaped notch 57. The outer edges of the V-shaped notches are flattened as at 58 to abut against the flat bottom surfaces of plungers 60 when the margin bar is in its functionally operative position as illustrated in Figs. 2, 3 and 8. The plungers 60 are preferably tubular and are urged toward the levers 52 by springs 61, the plungers being slidably journaled in the carriage frame 14. The flat surfaces 58 are relatively small in area but of sufficient size to insure that the vibration of the carriage frame will not cause displacement of the margin bar from its functionally operative position.

The levers 52 are oscillated during the operation of the machine to bring the margin bar 50 into and out of its functionally operative position. Thus, each time the carriage 13 is returned to its home position and a new sheet of paper is fed into it, the margin bar 50 is held in the position wherein it is illustrated in Fig. 2. Then when the handle 18 is displaced in a clockwise direction (Fig. 2) to lower the platen roll 19, the margin bar 50 is retracted to the position wherein it is illustrated in Fig. 4. Subsequently, when the platen roll 19 is raised to its uppermost position, the margin bar 50 is returned to the position wherein it is illustrated in Fig. 2. The means for oscillating the levers 52 to displace the margin bar 50 into and out of its functionally operative position preferably comprises links 65 pivoted to the levers 29 by the pin 25 and a pin 25a. The free ends of the levers 65 are provided with slots 66. Pins 68 projecting from the levers 52 ride in the slots 66 to provide lost motion connections between the levers 65 and 52. When the margin bar 50 is in its functionally operative position, the pins 68 rest against the inner ends of the slots 66 (see Fig. 2) so that the initial displacement of the lever 18 from the position wherein it is shown in Fig. 2 to the position wherein it is shown in Fig. 4 does not result in any displacement of the margin bar 50 as the pins 68 simply ride in the slots 66 until the platen roll 19 has clamped the paper to be duplicated between itself and the pressure roll 21. At this time, the pins 68 are engaging the outer ends of the slots 66 and continued displacement of the handle 18 in a clockwise direction (Fig. 4) causes the levers 65 to retract the margin bar 50 to the position wherein it is shown in Fig. 4. It will be noted that the margin bar 50 is withdrawn from the downward path of the platen roll 19 during the last portion of its downward stroke. When the handle 18 is displaced subsequently to raise the platen roll 19, the lost motion connection between the levers 65 and the levers 52 permits the margin bar 50 to remain in its retracted position until the platen roll has been withdrawn from its path.

When the margin bar 50 is in its retracted position, the flat bottom surfaces of the plungers 60 frictionally engage the rounded upper ends 75

of the levers 52 and prevent accidental displacement of the margin bar.

While we have shown and described certain embodiments of our invention, it is to be understood that it is capable of many modifications. Changes, therefore in the construction and arrangement may be made without departing from the spirit and scope of the invention as disclosed in the appended claims, in which it is our intention to claim all novelty inherent in our invention as broadly as possible, in view of the prior art.

We claim:

1. In a duplicating machine, a platen, a carriage mounted to be reciprocated over said platen, a yoke pivoted in said carriage, a platen roll journaled in said yoke, a pressure roll journaled in said carriage, a margin bar, and a single link between said yoke and said margin bar provided at one end with a lost motion connection.

2. In a duplicating machine, a platen, a carriage mounted to be reciprocated over said platen, a platen roll, means movably mounted in said carriage for journaling said platen roll, a margin bar, and a single link forming a lost motion connection between said movably mounted means and said margin bar, said link being carried at its opposite ends by said margin bar and said movably mounted means respectively.

3. In a duplicating machine, a platen, a carriage mounted to be reciprocated over said platen, a yoke pivoted in said carriage, a platen roller journaled in said yoke, a margin bar, levers pivoted in said carriage and carrying said margin bar, a spring pressed plunger frictionally engaging one of said levers, and means operatively connecting one of said levers to said yoke.

4. In a duplicating machine, a platen, a carriage mounted to be reciprocated over said platen, a yoke pivoted in said carriage, a platen roll journaled in said yoke, a margin bar, levers pivoted in said carriage and carrying said margin bar, means frictionally engaging one of said levers for holding it yieldingly in a predetermined position, and means including a lost motion connection between said yoke and one of said levers.

5. In a duplicating machine, a platen, a carriage mounted to be reciprocated over said platen, a yoke pivoted in said carriage, a platen roll journaled in said yoke, a margin bar, levers pivoted in said carriage and carrying said margin bar, one of said levers having a notch in its pivoted end, spring pressed means frictionally engageable with said notched end to hold said lever yield-

ingly in a predetermined position, and means operatively connecting one of said levers to said yoke.

6. In a duplicating machine, a platen, a carriage mounted to be reciprocated over said platen, a yoke pivoted in said carriage, a platen roll journaled in said yoke, a margin bar, levers pivoted in said carriage and carrying said margin bar, one of said levers having a substantially flat surface at its pivoted end, a spring pressed plunger having a substantially flat surface engageable with the first mentioned flat surface to retain said lever yieldingly in a predetermined position, and means operatively connecting one of said levers to said yoke.

7. In a duplicating machine, a platen, a carriage mounted to be reciprocated over said platen, a yoke pivoted in said carriage, a platen roll journaled in said yoke, a margin bar, levers pivoted in said carriage and carrying said margin bar, one of said levers having a substantially flat surface at its pivoted end, a spring pressed plunger having a substantially flat surface engageable with the first mentioned flat surface to retain said lever yieldingly in a predetermined position, and means including a lost motion connection between said yoke and one of said levers.

8. In a duplicating machine, a platen, a carriage mounted to be reciprocated over said platen, a platen roll, means movably mounted in said carriage for journaling said platen roll, a margin bar, a single link providing a lost motion connection between said movably mounted means and said margin bar, and a spring held latch for locking said platen roll in a functionally operative position with respect to said platen.

9. In a duplicating machine, a platen, a carriage mounted to be reciprocated over said platen, a platen roll, means movably mounted in said carriage for journaling said platen roll, a margin bar, means for yieldingly holding said margin bar in a predetermined position, and means including a lost motion connection between said movably mounted means and said margin bar.

10. In a duplicating machine, a platen, a carriage mounted to be reciprocated over said platen, a platen roll, means movably mounted in said carriage for journaling said platen roll, a margin bar pivoted in said carriage, means for holding said margin bar yieldingly in a predetermined position, and a lever connecting said movably mounted means to said margin bar.

HUBERT JAGGER.
JOHN W. HERNLUND.
